UNITED STATES PATENT OFFICE

VINCENT G. APPLE, OF DAYTON, OHIO, ASSIGNOR TO BENDIX BRAKE COMPANY, OF SOUTH BEND, INDIANA, A CORPORATION OF ILLINOIS

COMBINED STARTING AND REVERSING SWITCH

Application filed February 11, 1929. Serial No. 338,975.

This invention relates to switches for controlling electrically operable accessories of automotive vehicles.

An object of the invention is to provide a simple switch having contact means operable to make connections from a source of electrical energy to a motor to revolve the motor in a certain direction to accomplish one purpose, and other contact means adapted to connect the motor for opposite running for another purpose whenever the switch is in its natural inoperative position.

Another object is to provide a simple, inexpensive and effective structure for carrying the first object into effect.

This invention relates primarily to the construction of the switch mechanism here shown as adapted for the various purposes set forth and comprises a hollow insulation casing molded in situ about a plurality of terminals having contact ends arranged within the casing, in combination with pairs of flexible curved metal stamping connectors, arranged on opposite sides of the terminals within the casing, removed axially through the casing as a unit to bring one pair or the other of said connectors into contact with one side or the other of said terminals to bridge said terminals in pairs, the arrangement of which depends upon which pair of connectors performs the bridging operation.

Many other objects and meritorious features of the invention will be readily apparent to those skilled in the art to which the invention appertains, from a consideration of the following description, taken in conjunction with the drawings wherein—

Figs. 1 and 2 are diagrams of my switch connected to control a battery driven series motor, Fig. 1 showing the switch in its operative position and Fig. 2 in its normal inoperative position.

Figs. 3 and 4 show a plan and an edge view respectively of one of the switch terminals.

Figs. 5 and 6 are a plan and side view respectively of the molded switch body with terminals imbedded therein.

Figs. 7 and 8 are a plan and an edge view

respectively of one of the terminal connectors.

Figs. 9 and 10 are a plan and edge view respectively of the connector carrier.

Figs. 11 and 12 are assemblies of carriers and connectors.

Figs. 13 and 14 are plan and elevation respectively of a carrier spacer.

Figs. 15 and 16 are plan and elevation respectively of the pedal stem.

Fig. 17 is a plan view of the completed switch.

Figs. 18 to 22 are vertical sections taken through Fig. 17 at 18—18 to 22—22 respectively.

Figs. 23 and 24 are taken on the same section lines as 21—21 and 22—22 respectively with the switch in the position illustrated diagrammatically in Fig. 1.

The embodiment of my invention herein shown for illustrative purposes is adapted to provide two circuits through a battery driven series motor, the one circuit to revolve the motor in the one direction for cranking the engine of an automotive vehicle, and the other circuit for revolving the motor in the other direction for applying the vehicle brakes. But since it is neither necessary nor desirable to have the brakes applied at all times that the engine is not being cranked, a separate switch is preferably connected in the brake applying circuit to make rotation of the motor in its brake applying direction volitional.

Figs. 1 and 2 are diagrammatic illustrations of my switch and its connections to the motor and battery, with the separate switch in the brake applying circuit, Fig. 1 showing how the switch terminals are connected for cranking when the switch is depressed, and Fig. 2 showing how they are connected for braking when the switch is released.

Referring to Figs. 1 and 2, my improved switch 120 comprises a body 122, four terminals 124a, 124b, 124c and 124d, means 126a and 126b within the switch body to join terminals 124c and 124d and to ground terminal 124a when the switch is depressed for cranking as in Fig. 1, and means 126c and 126d within the switch body to join terminals 124a to 124c and 124b to 124d when the switch

is released to its normal inoperative position.

The separate switch 128 is effective to control braking only when switch 120 is in its normal position shown in Fig. 2. The battery and series motor elements illustrated by standard symbols are connected to the switch terminals by suitable cables as shown.

In the actual structure of switch 120, shown diagrammatically in Figs. 1 and 2, I provide metal terminals 124 shown in plan view Fig. 10 and edge view Fig. 4. A bolt hole 130 at the outer ends of each terminal facilitates attachment of the cables to the terminals. A knurled or otherwise roughened band 132 surrounds each terminal near its middle portion to improve its connection to the switch body.

The four terminals 124a, 124b, 124c and 124d are placed in a mold and a ring 134 of insulation is molded about the terminals at their roughened portions to hold them rigid and in suitably spaced relation. The ring 134 forms the body of the switch and has a rabbet 136 extending around its periphery at each end (see Figs. 5 and 6).

In actual practice the connectors, designated in Figs. 1 and 2 as 126a, 126b, 126c and 126d, consist of stampings 126, preferably of spring sheet copper, shown in detail in plan view Fig. 7 and edge view Fig. 8, cut to the outline 138 and bent to the curved contour 140. A squared opening 142 extends through the center of each connector.

To hold the several connectors 126 suitably spaced apart and insulated from each other I provide the carrier 144 shown in plan view Fig. 9 and edge view Fig. 10. Carrier 144 is composed of insulation, preferably molded to form, and has the metal insert 145 imbedded therein. Squared tenons 146 extend from one side as shown.

Two connectors 126 are assembled with a carrier 144 by placing the squared openings 142 over the squared tenons 146 as shown in Fig. 11. If then the assembly Fig. 11 is entered from the top into the assembly Fig. 5 so that the center line 148 is on the center line 150, and the assembly Fig. 11 is pressed downward against terminals 124a, 124b, 124c and 124d until the curved contour 140 of connectors 126 is straightened out against the bottom of carrier 144 the condition required in Fig. 1 of electrically connecting terminal 124c to 124d is adequately fulfilled, and if some provision is made for grounding insert 145 the terminal 124a will be grounded as there required.

Besides the assembly Fig. 11, a similar assembly Fig. 12 is provided. The assembly Fig. 12 comprises two of the connectors 126 and a carrier 144a similar to 144 except that insert 145 is omitted. This assembly Fig. 12 is entered from the bottom into the assembly Fig. 5 so that center line 148 comes on the center line 152. If it is then pressed upward against terminals 124a, 124b, 124c and 124d

until the curved contour 140 of connectors 126 is straightened out against the top of carrier 144a the condition required in Fig. 2 of electrically connecting terminals 124a to 124c and 124d is fulfilled. The flattening out of the curve 140 of the connectors against the terminals produces a wiping contact action tending to keep the contact surfaces clean.

To keep assembly Fig. 11 and assembly Fig. 12 correctly spaced within assembly Fig. 5, the spacer 154 shown in plan view Fig. 13 and edge view Fig. 14 is provided. This spacer is placed within assembly Fig. 5 in the plane of the terminals 124a, 124b, 124c and 124d. Assemblies Figs. 11 and 12 are then entered into the assembly Fig. 5, one from the top and the other from the bottom, on opposite sides of the spacer.

The spacer 154 has depressions 156 to clear the curved face 140 of connectors 126.

A metal plate 158 has an upwardly extending stem 160 and four tapped holes 162. (See plan view Fig. 15 and edge view Fig. 16). Four screws 164 extend through the four holes 166 of plate 144, of spacer 154 and plate 144a into tapped holes 162 to tie the entire movable part of the switch together (see Figs. 17, 18 and 19). A pedal tread 168 attached to the upper end of the stem 160 provides means whereon foot power may be applied to depress the movable part of the switch and a spring 170 is adapted to return it to its normal position. The heads of screws 164 extend through openings in the bottom of the switch to prevent rotative but to permit axial movement of the operable portion of the switch.

Covers 172 and 174 fit over rabbets 136 at each end of ring 134 to completely enclose the contact members. Two bolts 176 (see Fig. 19) extend through the covers and ring only, while two others 178 (see Fig. 18) extend through the covers and ring and also through the switch supporting bracket 180.

The sectional views Figs. 18 to 22 inclusive show the switch in its normal inoperative position with the upper pair of connectors 126a and 126b curving downward but separated from terminals 124, and the lower pair of connectors 126c and 126d flattened against the underside of the terminals. In this position the switch makes the connections shown in the diagram Fig. 2.

The sectional views Figs. 23 and 24 show the switch in the depressed starting position with the upper pair of connectors 126a and 126b flattened against the upper side of the terminals 124 and the lower pair of connectors 126c and 126d curving upward but separated from the terminals. In this position the switch makes the connections shown in diagram Fig. 1, the ground connection there shown being made through connector 126b, insert 145, a screw 164, plate 158

158, cover 172 to bracket 180 and thus to the vehicle frame.

5 While in the foregoing I indicate that my improved switch may be advantageously employed where it is desired to use an electric motor on an automotive vehicle, both for starting the engine and for applying the brakes, it will be understood that the switch has many other applications. For instance 10 by eliminating the separate switch 128 Figs. 1 and 2, the motor would revolve oppositely to its starting direction whenever the switch 120 was not being depressed for starting. Such an arrangement would be suitable 15 where the starting motor was to be revolved backwardly to drive a fan or a supercharging blower. Or, by substituting an automatic pressure operable switch for the switch 128 the motor could be made to serve the 20 twofold purpose of starting the engine and then pumping into a pressure tank only when the pressure in the tank falls below a predetermined value.

What I claim is:

25 1. In an electric switch, the combination of a substantially closed body having terminal members insulated from each other extending inwardly through the sides of the body and from its inner wall substantially midway of its length, connectors within the said body 30 between the said terminals and the one end adapted to engage the said terminals to connect certain of the said terminals in pairs, connectors within the said body between the said 35 terminals and the other end adapted to engage the said terminals to connect certain other of the said terminals in other pairs, and means to move the said connectors to engage the said terminals.

40 2. In an electric switch, the combination of a substantially closed body having terminal members insulated from each other extending inwardly through the sides of said body and from its inner wall substantially midway 45 of its length to divide the interior of the body into two compartments, a set of terminal connectors in each said compartment, each adapted to be moved into engagement with said terminals, the one set to connect certain 50 of the said terminals in pairs and the other set to connect certain other of the said terminals in pairs, means connecting the said sets of connectors for simultaneous movement the one set to go into engagement with said 55 terminals when the other goes out, and means to move the connecting means in both directions.

5. In an electric switch, a hollow body of 60 molded insulation having terminal members molded in situ in the walls of the body and extending inwardly from the inner wall substantially midway of its length, a member of insulating material endwise movable in said body carrying two sets of terminal connectors, the one set being positioned between the

said terminals and one end of said body and the other set being positioned between the said terminals and the other end of said body, manual means to move said member in the one direction to engage one set of said connectors with certain of said terminals and resilient means to return said member to engage the other set of said connectors with certain other of said terminals.

4. An electric switch comprising, in combination, a molded annular insulation casing, a plurality of pairs of circumferentially spaced apart terminals imbedded in the casing and extending radially therethrough intermediate its ends, a carrier plate arranged within the casing on one side of said terminals and provided with connectors adapted to bridge said terminals in pairs, a carrier plate arranged within the casing on the opposite side of said terminals and provided with connectors adapted to bridge the same terminals in the other pairs.

5. An electric switch comprising, in combination, a hollow insulation casing having two pairs of terminals imbedded therein and extending into the interior thereof, two pairs of connectors arranged within the casing and insulated from each other but secured together for movement as a unit and positioned one pair upon one side of the terminals and the other pair upon the opposite side of the terminals, means operable to move said connectors axially through the casing in one direction to cause one pair of connectors to bridge said terminals in pairs, and means yieldingly holding said connectors as a unit normally in the opposite direction to cause said other pair of connectors to bridge said terminals in the other pairs.

6. An electric switch comprising, in combination, a plurality of terminals insulated from each other and spaced apart, a pair of connectors arranged upon each side of the terminals and supported integrally for movement as a unit toward and away from the terminals to bring one pair or the other into engagement with the terminals to bridge said terminals in pairs.

7. An electric switch having two pairs of terminals arranged in substantially the same plane and two pairs of connectors arranged one pair upon one side of the terminals and the other pair upon the opposite side thereof, means normally yieldingly holding said connectors as a unit in one direction substantially perpendicularly to the plane of the terminals and to bridge said terminals in pairs to close a circuit through the switch, and means operable to move said connectors as a unit in the opposite direction against said yielding means to bridge said terminals in the other pairs to close a circuit through the switch.

8. An electric switch comprising, in combination, a hollow insulation casing having

- 5 a plurality of terminals imbedded therein and
extending into the interior thereof, two pairs
10 of curved flexible sheet metal connectors ar-
ranged within the casing one pair upon one
side of the terminals and the other pair upon
the opposite side thereof and connected to
15 together as a unit and insulated from each other,
means holding said connectors normally in
one direction as a unit to cause one pair of
connectors to bridge the terminals in pairs,
20 said connectors adapted to be moved manual-
ly in the opposite direction against the re-
sistance of said yielding means to cause the
other pair of connectors to bridge the termi-
nals in the other pairs.
- 25 9. An electric switch comprising, in com-
bination, a hollow insulation casing, a plu-
rality of terminals imbedded therein and ex-
tending into the interior thereof, a pair of
30 flexible connectors arranged within the cas-
ing on each side of the terminals, said con-
nectors being curved from the middle to the
ends toward the terminals and insulated from
35 each other and mounted for movement as a
unit axially through the casing to bring one
pair or the other into engagement with one
side or the other of said terminals bridging
40 them in pairs.
- 45 10. An electric switch comprising, in com-
bination, a plurality of pairs of terminals hav-
ing roughened intermediate portions, an insu-
lation casing molded in situ about said in-
50 termediate portions, a pair of connectors sup-
ported for movement within said casing and
adapted to bridge distinct pairs of terminals,
55 and means for simultaneously moving said
connectors.
- 60 11. In an electric switch, the combination
of an insulation casing molded in situ about
the intermediate portions of a plurality of
65 terminal members, a member supported for
axial movement within said casing, and a pair
70 of connectors secured within said casing to
said axially movable member on opposite
75 sides of the terminal members, each connector
80 of said pair being concave on its side adjacent
the terminals and adapted to flatten there-
85 against to wipe thereover upon making con-
tact therewith.
- 90 12. An electric switch comprising, in com-
bination, a casing, a plurality of pairs of ter-
minals carried thereby and exposed within
95 the casing, a connector assembly movably sup-
ported within the casing having spaced apart
100 connectors arranged on opposite sides of said
terminals and movable as a unit on a line nor-
mal to said terminals to bring the connectors
105 on opposite sides of said terminals respective-
ly into contact therewith to bridge the ter-
110 minals.
- 115 13. An electric switch comprising, in com-
bination, a casing, a plurality of pairs of ter-
minals carried thereby and exposed within
120 the casing, a connector assembly supported
125 for reciprocal endwise movement through the
